UNITED STATES PATENT OFFICE.

WILLIAM J. WRAY, OF PHILADELPHIA, PENNSYLVANIA, ASSIGNOR TO JOHN P. CROASDALE, OF BERWYN, PENNSYLVANIA.

TIMING MECHANISM.

1,405,961.

Specification of Letters Patent. Patented Feb. 7, 1922.

Application filed December 23, 1914, Serial No. 878,635. Renewed July 24, 1920. Serial No. 398,781.

To all whom it may concern:

Be it known that I, WILLIAM J. WRAY, a citizen of the United States, residing at Philadelphia, in the county of Philadelphia,

5 State of Pennsylvania, have invented a new and useful Timing Mechanism, of which the following is a specification.

My invention relates to improvements in timing mechanism. The object is to provide 10 means for indicating different periods of time, one comprised within another.

The invention comprises means for automatically indicating said included and including periods, means for automatically indicating the period of playing time still to elapse, means for automatically indicating an additional period of playing time in the event of an even score, including audible signals at the commencement and ending 20 of said periods, and means for indicating the character of the periods pending.

Referring to the drawings, which illustrate merely by way of example, a suitable embodiment of my invention:

25 Fig. 1 is a front elevation of an attachment for effecting my invention applied to standard clock works, the dial being removed.

Fig. 2 is a side view in section with the 30 clock dial in position.

Fig. 3 is a view in elevation partly in section, of the parts shown in Fig. 1, but in a different position and on an enlarged scale.

35 Fig. 4 is a section on line 4-4 of Fig. 3. Fig. 5 is a section on line 5-5 of Fig. 3.

Fig. 6 is a perspective view of one of the parts shown in Figs. 1 and 3.

Fig. 7 is a diagrammatic view showing 40 electrical connections and wiring.

Fig. 8 is a fragmentary side elevation in part section of parts shown in Fig. 2, on a slightly enlarged scale.

Fig. 9. is a rear elevation of the parts 45 shown in Fig. 8.

Fig. 10 is a section on line 10-10 of Fig. 8.

Fig. 11 is a section on line 11-11 of Fig. 8.

50 Fig. 12 is an elevation of parts shown in Figs. 1 and 3, but in a different position.

Similar numerals refer to similar parts throughout the several views.

I have shown the invention as comprising

an attachment applied to standard clock 55 works. It will be understood, however, that the invention may be embodied in the clock as originally manufactured.

Referring particularly to Figs. 1 and 3, lever 21 is fulcrumed at 42, connected at 60 one end with actuating rod 22, and pivotally connected at the other end with the vertically movable member 23, secured by guide screws 15 and 16 projecting through slots 25 and 26. Member 23 is provided with lug 65 27 extending at right angles thereto, its end recessed at 28, see Figs. 2 and 6. This recess 28 receives the detent lever 29, pivoted at 30, see Fig. 3. The free end of lever 29 is adapted to lie in groove 31 in the periphery of member 22, see Fig. 5. Member 32 is secured to toothed wheel 33, originally forming part of the striking mechanism of the clock, and rotates with wheel 33 in the counterclockwise direction. Member 32 is 70 75 provided with recess 34 in line with groove 31. The engagement of lever 29 in recess 34 arrests the movement of wheel 33.

On member 23 is mounted the spring member 36. Spring 38, supported at 39 80 and 40, presses at its free end upon projection 37, normally to maintain member 23 in the depressed position, as in Fig. 1. In this position of the parts, spring 36 is out of engagement with escapement lever 41, thus 85 permitting the normal operation of the same. Upon downward movement of rod 22, member 23 is raised against the tension of spring 38, and spring 36 engages lever 41 to lock it with the escapement wheel 44, see Fig. 90 3. At the same time, lever 29 is raised from the position resting in recess 34 to permit the movement of wheel 33.

This position of the parts is maintained until the rotation of wheel 33 brings recess 95 34 again beneath the detent finger of lever 29; whereupon member 23 resumes the depressed position and spring 36 is withdrawn from lever 41.

Means for arresting the movement of the 100 timing mechanism while wheel 33 is stationary, and for starting the timing mechanism again, will now be described.

Referring to Figs. 3 and 5, upon stud 46, secured to the frame of the clock, is mounted 105 the rotating element 47, which is maintained in position of adjustment by friction of the fixed leather washer 49, the required pres-

sure of which is secured by the metal washer 50 and screw 48. Pin 51 projects through the washers into stud 46 to prevent rotation of the washers. Element 47 is provided with 5 four projecting points 52, 53 with intermediate margins 54 in suitable arcs for engagement with escapement lever 41. Element 47 is provided upon its underside with the eight-toothed ratchet 55.

10 Member 56 is movably mounted and guided by means of the screws 59 and 60 projecting through the slots 57 and 58. Spring 62 supported by screws 63 and 64 engages stud 61 normally to maintain member 56 in the elevated position, as in Fig. 1. Manually operated rod 65 is provided for depressing member 56 against said spring tension. Member 56 carries the pawl 66, which co-operates with ratchet 55. Locking 20 dog 68 is mounted at 69 and normally held in engagement with the ratchet by spring 70.

When member 56 is depressed, pawl 66 moves ratchet 55 and consequently element 47, so that a projecting portion 52 will engage lever 41, to lock it with escapement wheel 44, as in Fig. 12. When rod 65 is released, member 56 is returned by spring 62 to its normal elevated position; pawl 66 engaging another tooth in ratchet 55.

30 With element 47 in the position shown in Fig. 12, a depression of member 56 will cause a movement of element 47 to the position shown in Fig. 1, by which movement projection 52 is withdrawn from lever 41 permitting it to swing free of escapement wheel 44, after which the adjacent projecting portion 54 first engages the lever 41, to force it back to the wheel, and then passes out of the path of said lever, that is, to the position shown in Fig. 1. This operation starts the timing mechanism.

As is well known, the game of basket ball comprises two twenty minute playing periods, a five minute rest period afterwards, 45 in case of a tie score, and an additional five minutes play, to play off the tie. Two minute "time-out" periods are also allowed in the event of injury to a player. The "time-out" periods are not deducted from 50 the actual playing time of the twenty minute periods. (No time-out is allowed during the extra five minutes' play in the event of a tie score.)

Means will now be described for indicating these various periods and the beginning and termination of the same.

Referring to Figs. 2 and 8 to 11, the hollow shaft 78 is secured by pin 74 to the minute hand arbor 72 of the clock, as shown in 60 Figs. 2 and 8. The metal disk 73 is rigidly and electrically connected to shaft 78, and is provided with the two electric contact points 75 and 76, lying in a radius of disk 73 and also in line with the minute hand of the 65 clock. Disk 73 is also provided with the in-

sulating plate 77. Upon shaft 78 is loosely mounted the plate 79 of non-conducting material recessed at 87 to accommodate the escapement wheel shaft 88. The conducting element 80, having the annular portion 81 70 surrounding shaft 78, is secured to plate 79, and is provided with binding post 82, and contact points 83 projecting through plate 79. Conducting element 84 is also secured to plate 79 and partially surrounds the 75 annular portion 81 of element 80, and is provided with binding post 85, and contact points 86 projecting through plate 79.

A thin metal element 89, Fig. 10, is secured to plate 79 by screws 90, and is provided with aperture 91 for the pin 92. A sheet 93 of mica or similar insulating substance, is secured back of elements 80, 84 and 89 to insulate same from the clock works.

The three armed spring member 96 is interposed between sheet 93 and stationary frame 95, one arm being provided with the projection 97 engaging in recess 98, to prevent its rotation with shaft 78 which it surrounds. The purpose of this spring is to 90 ensure the required pressure of engagement between the contact points 83 and 86 with contact points 75 and 76.

The adjusting element 100 is pivotally mounted at 101, and is provided at one end 95 with the transverse slot 102 through which projects the set screw 103. At the other end is provided pin 92 which projects into aperture 91 of element 89. By the movement of element 100 permitted by slot 102, plate 79 100 may be adjusted about its axis to advance or retard the engagement between contact points 75 and 83 and 76 and 86.

Referring now to Fig. 7, 83 and 86 represent the contact points indicated by similar numerals in Fig. 10. Points 83 are twenty minute contact points, and points 86 are five minute contact points. That is, in the normal or uninterrupted operation of the clock, contact point 75 will engage a point 83 every 110 twenty minutes; while contact point 76 will engage a contact point 86 every five minutes.

Wire 104 leads from one side of battery 105, through switch 106, to binding post 107 on the frame of clock works.

When point 75, to which point the current is free to pass through the works from post 107, contacts with a point 83, what may be termed a twenty minute circuit is completed through wire 108, plate 109, wire 110 to what 115 may be termed game bell 111, and wire 112 to the battery.

When point 76 contacts with a point 86, what may be termed a five minute circuit is completed through wire 113, switch 114, wire 115, plate 109, wire 110, bell 111, and wire 112 to the battery.

To the face of wheel 33, is secured a sheet of mica 116, through which project contact points 117, 118 and 119 from wheel 33 (Fig. 130

3). To the insulating block 120, secured to the stationary framework are the contact plates 122 and 127 provided with the binding posts 124 and 129 respectively. Plate 122 is 5 provided with the contact spring 126 adapted to contact with points 117 and 118. Plate 127 is provided with contact spring 130 adapted to contact with point 119.

When wheel 33 is locked against rotation, 10 as in Fig. 1, contact 126 projects between contact points 117 and 118. When wheel 33 is permitted to rotate, as indicated by the arrow in Fig. 7, point 117 makes electrical contact with spring 126 and completes the circuit, through binding post 124, wire 132, bell 133 and wire 112 to the battery, to cause the ringing of the time-out bell 133. The further rotation of wheel 33 brings point 119 15 into contact with spring 130, completing the circuit through binding post 129 and wire 134, buzzer 135, and wire 112 to the battery, to cause the ringing of said buzzer.

The continued rotation of wheel 33 brings 20 point 118 into contact with spring 126, the time-out circuit is again closed, and the time-out bell 133 rings again to indicate the end of the time-out period. This period, in the mechanism described, is of a duration of two minutes, and the period 25 from the first ringing of the bell 133 to the sounding of the buzzer, or warning signal, is one minute and forty-five seconds.

The speed of rotation of wheel 33 and, 30 consequently, the length of the periods between the ringing of the bells and the buzzer, is controlled by fan 131 which is connected by a train of gears with wheel 33, in the usual way.

The operation of the clock in the course 40 of a game of basket ball is as follows:

Assuming the game to be started with the minute hand of the clock in line with one of the twenty minute contact points 83, and, 45 consequently, contact point 75 in engagement with a point 83, switch 114 is open, and switch 106 closed. Rod 65 is actuated to start the timing mechanism as above described. Wheel 33 is maintained stationary by the detent lever 29.

50 Unless the game is temporarily stopped, the end of the playing period of twenty minutes is announced by the ringing of bell 111, when, the next contact point 83 is engaged by point 75.

55 If, however, a player should be injured, the game is stopped for a period of two minutes. By drawing down rod 22, member 23 is elevated, detent 29 is withdrawn from slot 34 and the rotation of the wheel 60 33 is started. Spring 36 locks lever 41 with escapement wheel 44, and stops the operation of the timing mechanism. The engagement of contact point 117 with spring 126 causes bell 133 to ring. In one minute 65 and forty-five seconds warning buzzer 135

rings upon the contact of point 119 with spring 130, and fifteen seconds later bell 133 rings, upon the engagement of point 118 with spring 126, to indicate the end of the time-out period. At this point, detent 70 lever 29 enters slot 34 to stop wheel 33. This permits the descent of member 23 and the release spring 36 from lever 41 of the timing mechanism. The timing mechanism now resumes the registration of the actual 75 playing time, from the point interrupted by the time-out period.

While lever 41 is held locked with the escapement wheel 73 the pendulum is held out of the perpendicular. The quick release 80 of lever 41 permits the swing of the pendulum to and past the perpendicular, and this, with the impulse given by the escapement wheel, enables the pendulum to pick up until it assumes normal operation. 85

When bell 111 rings, at the end of the playing period, another team may immediately take the floor, the first team resting during the playing of the period. In this event the operation of the clock continues as above described. If there is only one team, the timing mechanism may be stopped by drawing down rod 65.

If the score is even at the end of the two twenty minute periods and the tie is 90 to be played off, the device is started from the position of the parts shown in Fig. 12. Switches 106 and 114 are closed. Upon the engagement of point 76 with a point 86, bell 111 rings to call the players to the 100 floor. Upon the engagement of point 76 with the next point 86, bell 111 rings, again to indicate the termination of the five minute period for playing off the tie.

It will thus be seen that the periods of 105 time are measured accurately and the signals sounded automatically and with impartiality. The players are also able to determine by a glance at the clock, the amount of the playing period remaining unplayed.

It will be understood that the clock dial is sufficiently large, and that the clock is secured to the wall or other support, at a sufficient elevation, to be distinctly seen 115 from any part of the playing floor.

As the clock, thus positioned, is usually out of reach of the operator, the rods 22 and 65 are provided at their lower ends with rings, as shown in Fig. 1. To these 120 rings are secured cords or chains (not shown) which may extend any required distance and thus bring the control of said rods 22 and 65 within the reach of the operator, although he may be a substantial 125 distance from the timing mechanism.

As an example of means for indicating the character of the period being timed I have shown a "time-out" sign and actuating mechanism. Link 136 is pivotally con- 130

nected to levers 21 and 137. Lever 137 is fulcrumed at 138 and is provided near its free end with the bent-over portion 139, upon which rests the sign 140 hinged at 141. 5 The sign will thus be raised by the actuating rod 22 when it is desired to measure the "time-out" period. It will be lowered automatically at the end of said period, upon the descent of member 23.

10 It will be understood that the bells and buzzer are shown merely as examples of signaling device. It is obvious that other electrically controlled devices, whether visible or audible, may be inserted in the several circuits, either as substitutes for, or supplements to the devices shown.

What I claim is:

1. The combination of two timing-mechanisms, each for measuring different periods 20 of time, means for starting each timing mechanism and means for stopping one timing mechanism simultaneously with the starting of the other.

2. The combination of two timing mechanisms, each for measuring different periods 25 of time, means for starting each timing mechanism, means for stopping one timing mechanism simultaneously with the starting of the other and means for automatically 30 starting the former at the end of the period measured by the latter.

3. In combination with timing mechanism, means for arbitrarily starting the same, and means controlled by said timing mechanism 35 for signaling by different signals the beginning and end of different required periods of time.

4. In combination with timing mechanism, means adapted to be actuated at a distance 40 therefrom for arbitrarily starting the same and means controlled by said timing mechanism for signaling at the beginning and end of twenty minute periods.

5. In combination with timing mechanism, 45 means, adapted to be actuated at a distance therefrom, for arbitrarily starting the same and means controlled by said timing mechanism for signaling by differently sounding signals at the beginning and end of different 50 required predetermined periods.

6. In combination with timing mechanism, means for arbitrarily starting and stopping 55 the same, and means controlled by said timing mechanism for signaling at the beginning and end of twenty minute periods and of five minute periods, and means for rendering one of the signals ineffective.

7. In combination with timing mechanism, 60 arbitrarily actuated means for arresting the operation of the timing mechanism and automatic means for rendering ineffective said arresting means after a required period.

8. In combination with timing mechanism, 65 arbitrarily actuated means for arresting the operation of the timing mechanism and auto-

matic means, made effective by said arbitrarily actuated means, for rendering ineffective said arresting means after a required period.

9. In combination with timing mechanism, 70 arbitrarily actuated means adapted to be operated at a distance therefrom for arresting the operation of the timing mechanism and automatic means for rendering ineffective said arresting means upon the expiration 75 of a required period after said arbitrary actuation.

10. In combination with timing mechanism, arbitrarily actuated means for arresting the operation of the timing mechanism, 80 and automatic means, made effective by said arbitrarily actuated means, for rendering ineffective said arresting means after a required period, and means controlled by said automatic means for signaling at the beginning 85 and end of said period.

11. In combination with timing mechanism, arbitrarily actuated means for arresting the operation of the timing mechanism and automatic means, made effective by said 90 arbitrarily actuated means, for rendering ineffective said arresting means after a required period, and means controlled by said automatic means for signaling at the beginning and end of said period and at a required 95 intermediate period.

12. In combination with timing mechanism, a movable member, means for arbitrarily actuating the same in one direction, and means for automatically returning said 100 member to normal position, a projection on said member for engaging the escapement lever of the timing mechanism and means for controlling the timing mechanism during predetermined periods.

13. In combination with timing mechanism, a movable member, means for arbitrarily actuating the same in one direction, and means for automatically returning said 110 member to normal position, comprising a rotative element, and actuating means therefor, the said rotative element having a recess and a cooperating detent for engaging therein to arrest said rotation, and means connected with the movable member for 115 actuating the detent to release the rotating element.

14. In combination with timing mechanism, a movable member, means for arbitrarily actuating the same in one direction, 120 and means for automatically returning said member to normal position comprising a rotative element, actuating means therefor, the said rotative element having a recess, and a cooperating detent for engaging therein to 125 arrest said rotation, and means connected with the movable member for actuating the detent to release the rotating element arranged so that the detent maintains the movable member in the arbitrarily actuated posi- 130

- tion during a complete revolution of the rotating element.
15. In combination with timing mechanism, means for arbitrarily stopping the timing mechanism and means for automatically starting the same after a predetermined period, a source of electric energy, electric circuits, stationary contacts and signaling devices in said circuits and cooperating contacts moved by the timing mechanism whereby signals are produced at the beginning and end of predetermined periods.
16. In combination with timing mechanism, means for arbitrarily stopping the timing mechanism and means for automatically starting the same after a predetermined period, a source of electric energy, electric circuits, stationary contacts and signaling devices in said circuits, and cooperating contacts moved by the timing mechanism whereby signals are produced at the beginning and end of predetermined periods and whereby another signal is produced at an intermediate point of time.
25. 17. In a device of the character described, the combination of electric circuits, two series of stationary contacts spaced at required intervals and an element on and rotating with the minute hand arbor and provided with contacts for engaging said stationary contacts at different intervals of time.
18. In combination with timing mechanism, an electric circuit, a plurality of series of stationary contacts at required intervals relatively and signaling devices in said circuit, cooperating movable contacts mounted on and moving with the minute hand arbor for engaging said stationary contacts at required intervals of time.
19. In combination with timing mechanism, means for arbitrarily stopping the timing mechanism and means for automatically starting the same after a predetermined period, an electric circuit, a plurality of series of stationary contacts at required intervals relatively and signaling devices in said circuit, cooperating movable contacts moving with the operative parts of the timing mechanism for engaging said stationary contacts at required intervals, and means for cutting out of circuit one or more of said series of fixed contacts.
20. In combination with timing mechanism, a movable member adapted to be arbitrarily operated in one direction and automatically returned to the normal position, a rotatable member having surfaces adapted successively to engage the escapement lever of the timing mechanism and means for actuating the rotating element

upon arbitrarily operating the movable member.

21. In combination with timing mechanism, a movable member adapted to be arbitrarily operated in one direction and automatically returned to the normal position, a rotatable member having surfaces adapted successively to engage the escapement lever of the timing mechanism and means for actuating the rotating element upon arbitrarily operating the movable member, said rotatable member being so proportioned and arranged that when actuated it will first engage and then release and again engage and release the escapement lever to start the operation of the timing mechanism.

22. In combination with timing mechanism, means for measuring the time-out period comprising a motor and fan mechanism, means for arbitrarily starting the same and simultaneously stopping the timing mechanism, means for visually indicating said time-out period and also for audibly signaling at the beginning thereof, automatic means for signaling prior to the end of the time-out period and automatic means for signaling and releasing the timing mechanism to resume operation at the end of the time-out period.

23. In combination with timing mechanism, means for arbitrarily starting the same and means for signaling at the commencement of the period, means for signaling and stopping the timing mechanism for the time-out period of two minutes and simultaneously displaying an indicating device, automatic means for signaling fifteen seconds prior to the end of time-out period, and automatic means for signaling and starting the timing mechanism at the end of time-out period and causing the disappearance of the indicating device.

24. In combination with timing mechanism, means for arbitrarily starting the same and means for signaling at the beginning of the twenty minute period, means for signaling and stopping the timing mechanism for the time-out period of two minutes, automatic means for signaling fifteen seconds prior to the end of time-out period, automatic means for signaling and starting the timing mechanism at the end of time-out period, and automatic means for signaling at the end of the twenty minute period exclusive of the time-out period.

WILLIAM J. WRAY.
